(57) **CLAIM**

The ornamental design for a headgear, as shown and described.

DESCRIPTION

FIG. 1 is a front elevational view of a headgear showing my new design;

FIG. 2 is a right-side elevational view thereof;

FIG. 3 is a rear elevational view thereof;

FIG. 4 is a left-side elevational view thereof;

FIG. 5 is a top plan view thereof;

FIG. 6 is a bottom plan view thereof;

FIG. 7 is a perspective view thereof;

FIG. 8 is a front elevational view thereof wherein the top portion of the headgear is lifted, revealing the bottom portion of the headgear;

FIG. 9 is a right-side elevational view thereof;

FIG. 10 is a rear elevational view thereof;

FIG. 11 is a perspective view thereof; and,

FIG. 12 is a bottom perspective view thereof.
